UNITED STATES PATENT OFFICE

170,802

AUTOMOTIVE TOY

Elliot Handler, Los Angeles, Calif.

Application January 30, 1953, Serial No. 23,379

Term of patent 3½ years

(Cl. D34—15)

To all whom it may concern:

Be it known that I, Elliot Handler, a citizen of the United States, residing in Los Angeles, county of Los Angeles, State of California, have invented a new, original, and ornamental Design for an Automotive Toy, of which the following is a specification, reference being had to the accompanying drawings, forming part thereof.

Figure 1 is a perspective view of an automotive toy, showing my new design.

Figure 2 is a front elevational view thereof;

Figure 3 is a rear elevational view thereof;

Figure 4 is a top plan view thereof;

Figure 5 is a side elevational view thereof; and

Figure 6 is a bottom plan view thereof.

I claim:

The ornamental design for an automotive toy, substantially as shown.

ELLIOT HANDLER.
